UNITED STATES PATENT OFFICE.

BENEDICT C. OSKIN, OF CHICAGO, ILLINOIS.

SAFETY RAZOR.

Application filed July 9, 1925. Serial No. 42,560.

To all whom it may concern:

Be it known that I, BENEDICT C. OSKIN, a citizen of the United States, and resident of Chicago, in the county of Cook and State 5 of Illinois, have invented certain new and useful Improvements in Safety Razors; and I do hereby declare the following to be a full, clear, and exact description of the invention, such as will enable others skilled 10 in the art to which it appertains to make and use the same.

This invention relates to safety razors, and especially to improvements in razors of the "Auto-Strop" type.

15 The auto-strop type of safety razor is provided with a combed guard carrying an upstanding lug on each side, and two rotative shafts are journaled at each end in said lugs; said shafts carrying intermeshing gears. A clamping plate, of rigidly resili- 20 ent material is non-rotatively mounted on the top shaft and the blade is forced between said clamps and held in shaving position by the inherent resiliency of the plates.

25 The plates must be sufficiently strong to retain the blade in proper position for shaving, and it is therefore rather difficult to force the blade between them, the manipulation of the blade often resulting in injury 30 to the hands of the operator. After insertion the plates and blade are clamped to the guard by means of a lever projecting at the rear.

In stropping the razor the plates are released from the guard and the upper shaft is rotated to swing the former at an angle to the latter, and the strop is passed beneath the lower shaft. The razor is then moved backwardly and forwardly along the strop, the frictional contact of the lower shaft upon the surface of the strop serving to rotate the upper shaft and present alternate sides of the blade to the strop as the direction of reciprocation is reversed.

45 The object of this invention is the provision of a razor of the type above referred to, equipped with means greatly facilitating the operation of inserting a blade between the holding plates, and releasing said blade therefrom, and without danger to the hands of the operator, said means also being operable to secure the blade to the guard.

50 Other objects of the invention will be made apparent in the following specifications, when read in connection with the

accompanying drawings forming a part thereof.

In said drawings;

Fig. 1 is a perspective view of a razor embodying my invention. 60

Fig. 2 is a section taken on the line 2—2 longitudinally through the razor and handle, and

Fig. 3 is a perspective view showing the operation of inserting or removing a blade, 65 a portion of one of the plates being broken away.

Now referring specifically to the drawings, in which similar reference characters indicate like parts throughout the several 70 views, the embodiment of the invention here shown comprises a metallic body portion 1 which is screw-threaded at its base adapting it for co-operation with threads interiorly provided on a tubular handle 2, carrying a brush 3, a drip vent 4 being provided in the bottom of the handle. Obviously a solid or any other kind of handle may be substituted if desired. The body 1 terminates in a reduced shank 5, carrying a 75 screw-threaded lug 6, adapted for screw-threaded engagement with the aperture provided in a razor guard 7, as will be understood. The guard 7 is provided with an elevated flange 8 on one side, and with a 80 larger flange 9 extending upwardly and thence inclined downwardly, terminating in a comb 10, as clearly shown in Figs. 2 and 3.

The guard 7 carries upstanding lugs 11 85 and 12, one on each side, said lugs being provided with apertures in vertical alignment to receive the ends of shafts 13 and 14. Pinions 15 and 16 are carried by those 90 ends of the shafts projecting through the lug 12, as shown, said pinions being in intermeshing engagement whereby rotation of one shaft will cause rotation of the other shaft in a reverse direction.

The present invention includes a blade 100 A, of flat thin steel of the general shape of the "Gillette" blade, and as clearly shown in Fig. 3. The blade is centrally provided with an elongated rectangularly shaped opening 17, and with smaller oval shaped 105 openings 18 and 19, positioned on each side of the opening 17, and provided with straight side walls and rounded end walls.

Two blade-holding plates B and C are mounted upon the shaft 13. The plate B is 110

- 2
- provided with collars 20, 21, each of which surrounds the shaft 13, and is secured thereto, adjacent the inner face of one of the lugs 11 and 12, whereby any rotation of the shaft 13 will swing the plate B. The plate C is provided with an elongated collar 22 which loosely surrounds the shaft 13, whereby the plate is rotatable around the shaft. As shown in Fig. 3, a coiled spring 23 surrounds that portion of the shaft 13 between the collars 20 and 22, said spring exerting a tendency to retain the collar 22 in contact with the collar 21. It will be obvious however that the plate C is not only rotatable about the shaft 13, but is slideable longitudinally thereon against the tension of the spring 23.
- The plate C is centrally provided with an integrally-formed locking detent 24, which is struck from the metal composing the plate, said detent extending outwardly from the plate and being provided with a backwardly curved tongue 24'. At the left of the detent 24 is formed an aperture 25, provided with a straight wall adjacent the detent 24, and, on the other side of the detent 24, is provided a similarly shaped aperture 26, with a straight wall remote from said detent.
- The plate B is centrally provided with an aperture 27, having a straight wall on the left. On the left side of said aperture is formed a detent 28, which is struck from the metal of the plate and is provided with a lip directed towards the aperture 27. An exactly similar detent 29 is provided on the other side of the aperture 27, it being noted that the lip is turned away from the aperture 27.
- As clearly illustrated in Fig. 3, the portion 9 of the guard 7 is centrally provided with an aperture 30, of the exact size and configuration as the aperture 27 in the plate B, and adapted for registration therewith when the plate B is laid flat on said portion 9.
- With the instrumentalities provided as described, when the razor blade A is to be inserted between the plates B and C, the blade is laid onto the plate B so that the detents 28 and 29 pass through the apertures 18 and 19 respectively, and the blade is then moved to the left so that the detents overlie the body portion of the blade. The plate C is then swung around the shaft 13 towards the plate B, and, since the blade has been moved to the left, the tongue 24' will pass through the aperture 17 in the blade, but will contact the body portion of the plate B, adjacent and at the left of the aperture 27 therein. Also the body portions of the plate C, adjacent and at the left of the apertures 25 and 26, will also contact the detents 28 and 29, on the plate B, and in view of these facts the plate C, in this position, cannot interlock with the blade and plate B. But, simultaneously with the rotation of the plate C around the shaft 13, the operator presses upon the plate C and pulls it to the right, against the compression of the spring 23. This operation changes the position of the plate C, and permits the passage of the detents 28 and 29 through the apertures 25 and 26 respectively, which are then in registration with said detents, and causes the tongue 24' to pass into registration with the aperture 27 and permits it to pass therethrough. In this position the lateral pull of the plate C to the right is released, and the spring 23 restores it to its normal position, whereupon the detents 28 and 29 engage that surface of the plate C, remote from the plate B, and the tongue 24' engages that surface of the plate B, remote from the plate C, the blade being securely locked between the plates, and retained in that position by the spring 23.
- The above is the stropping position of the razor, and it will be obvious that the strop may be passed beneath the shaft 14, Fig. 2, and that the stropping operation may be carried out in the usual manner.
- To secure the blade A in shaving position, as shown in Figs. 1 and 3, the assembled plates and blade are laid down onto the portion 9 of the guard 7, but the tongue 24' will strike that portion of the guard 9 to the left of the aperture 30 and will not enter said aperture. The plate C is again pulled to the right, sliding along the shaft 13, and over the blade A, until the tongue 24' registers with the aperture 30, whereupon the tongue enters said aperture and the spring 23 pushes the plate C to the left and the tongue 24' engages the lower face of the portion 9, adjacent the said aperture 30, firmly locking the assembled plates and blade into shaving position, with the edge of the blade over the comb 10.
- Manifestly a reverse movement of the plate C will permit unlocking of the plates and blade from the guard, or will permit ready disassembly of the blade and the plates B and C, and since it is not necessary to touch the blade A, during the locking or unlocking operations, such manipulations are not accompanied by any danger of injury to the operator. Moreover, all the parts of the device are completely disassembled when the blade A is removed, and are therefore easily cleaned and dried, preventing the formation of rust. The cleaning between the clamping plates of the ordinary "Auto-Strop" structure is not possible. It is also to be noted that the tongue 24' and the detents 28 and 29 all engage the straight walls defining the apertures 25, 26, 27 and 30, and hence any rotative movement of the blade A is impossible.
- Modifications of the herein disclosed structure may be suggested to those skilled

in the art, but my invention covers all such embodiments as fall fairly within the scope of the appended claims.

What I claim is:

5 1. A safety razor including two shafts geared together, and two blade-holding plates mounted on one of said shafts, one of said plates being rotatable with respect to said shaft.

10 2. A safety razor including two shafts geared together, and two blade-holding plates mounted on one of said shafts, one of said plates being rotatable with respect to said shaft, and movable longitudinally 15 thereof.

3. A safety razor including two shafts geared together, and two blade-holding plates mounted on one of said shafts, one of said plates being rotatable with respect 20 to said shaft, and movable longitudinally thereof, and means for resiliently resisting such longitudinal movement of said plate.

4. A safety razor including two shafts geared together, and two blade-holding 25 plates mounted on one of said shafts, one of said plates being rotatable with respect to said shaft, and movable longitudinally thereof, and means for resiliently resisting such longitudinal movement of said plate, said 30 means comprising a coiled spring surrounding said shaft and positioned in the path of such movement.

5. Blade-holding means for safety razors comprising a rotative shaft, a plate mounted 35 for movement around and longitudinally of said shaft and provided with a detent adapted for extension through an aperture in a blade, a second plate fixed on said shaft and provided with means co-operating with 40 said detent to retain said blade between said plates, a guard, and means carried by said guard co-operating with said detent to secure the plates and blade to the guard when 45 said first mentioned plate is moved in one direction longitudinally of said shaft.

6. A safety razor including a rotative shaft, a plate rigidly secured to said shaft and provided with two detents extending 50 therefrom and with an aperture, another plate loosely mounted on said shaft and capable of rotative and longitudinal move-

ment with respect thereto, said loosely mounted plate being provided with two apertures and a detent so positioned as to be brought into registration, respectively, 55 with the detents and the aperture on the rigid plate when the loosely mounted plate is shifted longitudinally of said shaft, in combination with a blade apertured to receive the detents on both plates when the loosely mounted plate is shifted longitudinally of the said shaft.

7. A safety razor including a rotative shaft, a plate rigidly secured to said shaft and provided with two detents extending 60 therefrom and with an aperture, another plate loosely mounted on said shaft and capable of rotative and longitudinal movement with respect thereto, said loosely mounted plate being provided with two 65 apertures and a detent so positioned as to be brought into registration, respectively, with the detents and the aperture on the rigid plate when the loosely mounted plate is shifted longitudinally of said shaft, in combination with a blade apertured to receive the detents on both plates when the loosely mounted plate is shifted longitudinally of the said shaft, and with means 70 tending at all times to restore said loosely mounted plate to normal position on said shaft.

8. A safety razor including a rotative shaft, a plate rigidly secured to said shaft and provided with two detents extending 75 therefrom and with an aperture, a guard provided with an aperture, another plate loosely mounted on said shaft and capable of rotative and longitudinal movement with respect thereto, said loosely mounted plate being provided with two apertures and a 80 detent so positioned as to be brought into registration respectively, with the detents and the aperture on the rigid plate and with the aperture in said guard, when the loosely mounted plate is shifted longitudinally of said shaft, in combination with a blade apertured to receive the detents on both plates when the loosely mounted plate is shifted longitudinally of the said shaft.

In testimony whereof I affix my signature.
BENEDICT C. OSKIN.
